CHILD'S GUN GAME

Hervey Warren Small, Dubois, Idaho

Application June 4, 1958, Serial No. 739,767

4 Claims. (Cl. 46—116)

This invention relates to games and toys especially designed for use by children, the primary object of the invention being to provide a figured toy simulating an animal depicted as emerging from an opening in an earth mound, and a pistol located as pointed at the opening, novel means being provided for returning the figured animal to the interior of the opening, simultaneously with the firing of the pistol, simulating the actions of a live animal.

An important object of the invention is to provide a game of this character including a base or stand on which a pistol and a simulated earth mound are mounted, the simulated earth mound having an opening in which a toy simulating an animal is mounted, mechanism being provided for setting in motion the simulated animal to a position partially emerged from the opening of the earth mound, simultaneously with the cocking of the pistol for firing.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings:

Figure 1 is a plan view of a game, constructed in accordance with the invention.

Fig. 2 is a bottom plan view of the game stand.

Fig. 3 is a longitudinal sectional view through the game support and illustrating the toy constructed to simulate an animal, as partially emerged from the opening of the earth mound.

Fig. 4 is a sectional view taken on line 4—4 of Fig. 3.

Fig. 5 is a fragmental plan view of the figured toy support and operating mechanism.

Referring to the drawings in detail, the toy or game comprises a base indicated generally by the reference character 5, the base being provided with transverse supporting bars 6 and 7 secured to the under surface thereof adjacent to the front and rear ends of the base 5, respectively.

These supporting bars 6 and 7 are of such width that they will support the base 5 in spaced relation with the surface on which the game or toy is supported, providing a clearance for the game piece actuating bar and game piece support indicated by the reference character 8.

A stop bar 9 is secured to the under surface of the base 5 adjacent to the bar 6, and provides a stop for the sliding game piece actuating bar or support 8, as clearly shown by Fig. 3 of the drawings.

The bar 7 is formed with a cut out portion 10 through which the bar 8 slides, the bar 8 also sliding under the U-shaped bracket 11 secured to the under surface of the base 5, at a point substantially intermediate the ends thereof.

Secured to the upper surface of the base 5 is a

2

member 12 which is constructed to simulate an earth mound, the member 12 being provided with a bore 13 that extends therethrough, the bore providing an opening in which the game piece or figured toy 14 is mounted.

As better shown by Fig. 3 of the drawings, the bar 8 is provided with a cut out portion 15 in which the offset end 16 of the supporting rod 17 is secured, as by means of the pin 18.

10 As shown, the supporting rod 17 is inclined upwardly to rest directly on the lower surface of the bore 13, the upper end of the supporting rod 17 being secured to the figured game piece 14, by means of the screw 19.

15 Pivotedly mounted adjacent to the forward end of the base 5 is an arm 20 that is secured to the pivoted plate 21 that in turn is pivotally mounted on the base 5, at 22.

15 Mounted on the forward end of the arm 20 is a pin 23 that extends through an opening 24 formed in the base 5 near the rear end thereof, the pin 23 being of a length to extend into the opening 25 formed in the game piece actuating bar or support 8, when the bar 8 is moved to its cocked position, as better shown by Fig. 3 of the drawings. A spring indicated by the reference character 26 is secured to the arm 20 near the rear end thereof, the spring 26 having its forward end riding in the groove 27 formed in the upper surface of the bar 8, near the rear end thereof. Thus it will be seen that due to this construction, the pin 23 is biased

30 towards the bar 8 and when the bar 8 has been moved to the position as shown by Fig. 3 of the drawing, the pin 23 will pass through the registering openings 24 and 25, temporarily locking the bar 8 in a cocked position with the figured game piece extending partially 35 through the opening of the earth mound, as shown by Fig. 3.

30 A pistol indicated generally by the reference character 28 is supported at the rear end of the base, and the grip 29 thereof is provided with an opening in its lower 40 end to receive the upwardly extended right angled end 30 of the arm 20.

30 A coiled spring 30' has one of its ends connected to the game piece actuating bar or support 8, near the rear end thereof, while the opposite end of the coiled spring is connected to the bar 6 at 31. Due to this construction it will be obvious that the spring normally moves the bar 8 towards the front end of the base 5.

30 The pistol is so constructed and arranged that the barrel thereof is pointed or aimed at the figured toy 14. Thus it will be seen that when the pistol is gripped and the trigger 29' thereof is pulled and the pistol tilted rearwardly, the pin 23 will move from the registering openings, allowing the bar 8 to move forwardly biased by coiled spring 30' which is shown as having one of its ends secured to the bar 8 by means of pin 33, with the opposite end thereof secured to the end bar 6, by means of hook 31, as previously described.

32 Secured to one end of the bar 8 is a finger piece 32 which, when pulled rearwardly, will cause the gun 60 to be cocked and the figured toy moved to the position as shown by Fig. 3, ready for firing.

32 From the foregoing it will be seen that due to the construction shown and described, I have provided a game embodying a movable figured toy and a pistol arranged in such a way that the barrel of the pistol is directed or aimed at the figured toy emerging from an opening in the member 12 simulating an earth mound.

32 With each movement of the pistol 28 to move the pin 23 from the registering openings 24 and 25, it will be seen that the figured toy 14 will move with the bar 8 to a position within the opening 13.

What is claimed is:

1. A combined toy and game, comprising a base, a simulated earth mound having a bore formed therein, secured on said base, a bar slidably mounted on said base, a figured game piece simulating an animal, disposed within said bore, means for securing said game piece on said bar for movement longitudinally of said bore, a toy pistol pivotally mounted on the base aimed at said game piece, a spring member connected between said bar and base normally biasing the bar towards the front end of said base, means for normally holding said spring under tension with said game piece partially emerged from said bore, and means controlled by said pistol for releasing said bar to the action of said spring, returning said game piece to a position wholly concealed within said bore. 10
2. A toy comprising a base, a housing embodying a simulated earth mound mounted on said base at the forward end thereof, said housing having a bore therein, a bar slidably mounted under said base, a coiled spring connected between said bar and base normally biasing said bar towards the front end of said base, a figured toy member supporting rod secured at one of its ends to said bar and extending upwardly therefrom, means for securing said figured toy member to the other end of said rod within said bore of said housing for movement longitudinally of said bore, means for normally holding said spring tensioned with said game piece partially emerged from said bore, and manually controlled mechanism for releasing said bar to the action of said spring for moving said toy member to a position wholly concealed within said bore. 20
3. A toy comprising a base, a housing mounted on said base, a bar having an opening, slidably mounted on said base, a figured game piece secured to said bar, 30
- 5 a coiled spring connected between said base and bar adapted to bias said bar towards the rear end of said base, a pistol pivotally mounted on said base, a pin depending from said pistol movable into said opening of said bar normally holding said bar against the action of said spring, and said pin adapted to move from its position within said opening releasing said bar for rearward movement under the action of said spring, moving said figured game piece wholly within said housing. 15
4. A toy comprising a base, a housing simulating an earth mound having a bore, mounted on said base, a bar mounted for longitudinal sliding movement on said base, an arm secured to said bar extending into said bore of said housing, a figured member secured to the upper end of said arm movable within the bore, said bar having an opening, a plate pivotally mounted on said base, a toy pistol mounted on said plate, a pin extending downwardly from said plate movable into said opening of said bar normally holding said bar against sliding movement, a coiled spring connected between one end of said base and bar normally biasing said bar forwardly, and said toy pistol adapted to pivot upwardly removing said pin from said opening releasing said bar to the action of said spring whereby said game piece is moved wholly within said bore of said housing. 25
